Patented Jan. 19, 1915.

UNITED STATES PATENT OFFICE.

JUSTUS W. FRY, OF SEATTLE, WASHINGTON

TELEPHONE REPEATER SYSTEM.

1,125,832.

Specification of Letters Patent.

Patented Jan. 19, 1915.

Application filed April 2, 1913. Serial No. 756,394.

To all whom it may concern:

Be it known that I, JUSTUS W. FRY, a citizen of the United States, residing at Seattle, in the county of King and State of Washington, have invented certain new and useful Improvements in Telephone Repeater Systems, of which the following is a specification:

This invention relates more particularly to long distance telephone systems.

The object of the invention is the improvement of systems of this character whereby voice sounds may be transmitted from either end of the line without interference or retardation from other voice sounds by providing means under the control of an operator whereby the line may be used to carry in but one direction at a time.

20 The invention consists in the novel adaptation and combination of devices, as will be hereinafter described and claimed.

In the accompanying drawings, Figure 1 is a diagrammatic view of a telephone system provided with metallic controlling circuits embodying the present invention. Figs. 2 and 3 are similar views of modified forms of the controlling circuits with the same grounded.

25 In Fig. 1 is shown a telephone system having two stations A and A¹ and an intermediate relay station B, although it is to be understood that the invention is applicable to systems in which a plurality of relay stations may be used.

The telephones are or may be of the usual type having transmitters 5 and receivers 6. A relay station is provided with relay magnets 7 and 7¹ which, upon occasion, serve 30 to operatively connect the line-wires of stations A and A¹. The magnet armatures 8 and 8¹ are secured to arms 9 and 9¹.

10 and 10¹ represent switches or keys for closing circuits hereinafter designated as 35 controller circuits. The controller circuit for station A comprises wires 11 and 12 which are joined to line-wires 13 and 14 and which, in turn, are connected to the helix of the magnet 7 by wires 15 and 16. The 40 wire 15 is an open one having terminals 17 which are connected by a gap closer 18 provided on relay arm 9¹ when the latter is in its inoperative position with respect to the magnet 7¹. Included in such circuit is a battery 19 and resistance coils indicated by 45 20. The controller circuit for station A¹

is in like manner comprised of wires 11¹ and 12¹, line-wires 13¹ and 14¹, and wires 15¹ and 16¹ which embrace the winding of the magnet 7¹ and have for wire 1¹ terminals 17¹ which are arranged to be connected by a gap closer 18¹ carried on the relay arm 9¹ of the magnet 7¹ when the arm is swung therefrom upon deenergizing the magnet. Also included in the controller circuit of 50 station A¹ is a battery 19¹ and resistance coils, as 20¹. For the talking circuits there are provided at the relay station suitable voice amplifiers or high power repeaters C and C¹.

55 The receiver member 21 of repeater C is connected by wires 22 and 23 with the line-wires 13 and 14 through the medium of condensers 24. Similarly, the receiver member 21¹ of the other repeater C¹ is connected by wires 22¹ and 23¹ through condensers 24¹ with the line-wires 13¹ and 14¹.

60 The transmitter member 25 of repeater C is connected by wire 26, which includes a battery 27, with the relay arm 9 which serves as a conductor. The companion wire 28 from said transmitter member is connected with the primary of induction coils 29 whose secondary is connected by wire 30, as shown, with the line-wire 14 through the medium 65 of a condenser. Similarly, the primary of induction coils 29¹ is connected by a wire 28¹ with the transmitter member 25¹, while the secondary of the coils is connected by wire 30¹ with the line-wire 14¹. The other 70 wire 26¹ from the transmitter member includes a battery 27¹ and is connected with the relay arm 9¹.

75 The primaries and secondaries of the respective induction coils are bridged and thence are connected by wires 31 and 31¹ provided with terminals 32 and 32¹. Supplementary wires 33 and 33¹ connect line wires 13¹ and 13 through condensers 34¹ and are provided with terminals 35 and 35¹. 80 The terminals 32 and 35 are disposed to be contacted by the arm 9 when the latter is attracted by the magnet 7.

85 In the operation of the aforesaid embodiment of the invention, the controller circuits are associated with the talking circuits so that a person at either station A or A¹ by closing his controller circuit not only renders the other controller circuit temporarily inoperable, but also prevents the 90 talking circuit from the remote station from being used except for receiving purposes,

hence there will be no interference or retardation by a confusion of voice sounds on the line. More specifically, assuming that a person at station A is to talk over the line, 5 the key 10 is utilized to put battery 19 to line resulting in the energizing of magnet 7 to attract the armature 8 to draw the arm 9 away from contacts 17¹ and into operative contact with terminals 32 and 35, to complete 10 the talking circuit from station A. By withdrawing the arm from contacts 17¹ the controller circuit for station A¹ is obviously caused to be inoperable to effect the energizing 15 of the magnet 7¹; consequently the arm 9¹ is rendered incapable of being brought into contact with terminals 32¹ and 35¹ to close the talking circuit leading from station A¹.

The modification of the controller circuits 20 shown in Figs. 2 and 3 are substantially similar to those shown in Fig. 1 except that in Fig. 2 a relay is actuated from line wires as 13, 13¹ through the medium of bridging or simplex coils 40; one of such coils being 25 connected by wire 12² with main battery 19² and the complementary coil is connected by wire 16² with the relay magnet. The contacts 32 and 35 are respectively connected, as shown, by wires 31² and 33² with a ground 30 and the simplex coil of the line-wires 13² and 14². The wire 11² in this case is also grounded.

In Fig. 3, a relay is connected by wire 16³ with one side of a metallic circuit 13-14³, 35 the controller key is connected by wire 12³ including battery 19³, and the line-wire 11³ is grounded. Contact 35 is connected by wire 33³ with the referred to circuit wire, and the other wire 31³ extending from contact 32 is also grounded.

The operation of the devices illustrated in Figs. 2 and 3 will, it is thought, be understood without further description.

What I claim, is—

45 1. In a telephone system, the combination of two repeating instruments, two normally open local circuits respectively including the receivers of the repeating instruments, normally open electrical connections between 50 the transmitter of each of said repeating instruments and the other local circuit, a nor-

mally open controller circuit for each of said local circuits, and means regulated by the closing of either of said controller circuits whereby one of the aforesaid electrical connections is closed to render the telephone system operative from one direction only.

2. In a telephone system, the combination of two repeating instruments, two normally open local circuits respectively including the receivers of the repeating instruments, normally open electrical connections between the transmitter of each of said repeating instruments and the other local circuit, a relay-magnet for each of said local circuits, a normally open controller circuit for each of said local circuits and embracing the windings of the respective relay-magnets, and means regulated by the closing of either of said controller circuits and effected through the energizing of the respective relay-magnets whereby one of the aforesaid electrical connections is closed to render the telephone system operative from one direction only.

3. In a telephone system, two normally incomplete local circuits each provided with a telephone receiver and a transmitter, a relay instrument for each of said local circuits, line connections between the local circuits and including said relay instruments, and a normally incomplete controller circuit including a battery for each of said local circuits and means coöperating with the aforesaid circuits and line connections which are regulated by the closing of either of said controller circuits so that the associated transmitter and the remote receiver are caused to be operable to transmit sounds therebetween and thereby causing the remote transmitter and the adjacent receiver to become inoperable for the transmission of sounds therebetween until the referred to controller circuit is again open.

Signed at Seattle, Wash., this 26th day of March, 1913.

JUSTUS W. FRY.
